DRAFTING INSTRUMENT

Hermann Anderegg, Malakoff, France, assignor
to La Cellophane, Paris, France, a French company

Application August 11, 1950, Serial No. 178,845
In France June 2, 1947

2 Claims. (Cl. 33—79)

1

This invention relates to drafting instruments and more particularly to ruling devices mounted for parallel motion over the surface of the drawing board.

Drafting instruments of this character, whether of parallelograms or band type, generally include a forearm supporting the head of the instrument, which is fitted with the right-angled rules, linked to another arm which in turn swings around an anchoring means attached to the drawing board.

When the drawing board is inclined, the assembly described above tends to fall of its own weight towards the foot of the board. It is therefore desirable to balance drafting instruments intended for work at a certain inclination in such a manner that the draftsman can, without appreciable effort, displace the head over the entire surface of the board, and that this head will remain at a point where it has been placed without tending to shift when re-released. The present invention accomplishes this purpose in a simple and improved manner.

This application is a continuation-in-part of my co-pending application Serial No. 109,285 filed August 9, 1949, for Drafting Instrument.

In the drawing the figure is a plan view of a drafting instrument embodying the present invention.

This device is shown for purposes of illustration as applied to a parallelogram type instrument. However it is equally applicable to a band instrument.

In the figure a drawing board 1 is mounted on a suitable support and is adapted to be inclined in any position from horizontal to vertical. An anchoring bracket 2 is attached to the board and carries parallelogram links 3 and 4 which are pivoted to the bracket 2 at 5 and 6 respectively. The other ends of the links 3 and 4 are pivoted at 7 and 8 respectively to a block 9 to which parallelogram links 10 and 11 are pivoted. A support 12 carrying the drafting head 13 is attached to the second parallelogram by means of links 10 and 11 pivoted at 14 and 15 respectively. The drafting head 13, which is rotatable about its axis, carries a set of rules 16 and 17 set at right angles in the usual manner.

This assembly is balanced, pursuant to the present invention, in the following manner:

A steel wire 20 attached at 15 engages the groove of a pulley 21 which is mounted by a pin 22 on the block 9. The radius of this pulley 21 may vary according to the type of in-

2

strument involved. It is not, however, essential that the position of the pin 22 coincide with the center of the quadrilateral formed by the links 3 and 4 and the block 9. The wire 20, after passing around the pulley 21, is attached at 23 to one end of a spring 24 which in turn is attached at 25 to the frame 26 of a trolley 27 riding on a flexible rod 28 having a suitable curvature. The rod 28 is made of elastically deformable material, such as piano wire and is adapted to flex in response to an excessive pull by the spring 24 which may occur in certain positions of the drafting head. The spring 24 normally balances the pull of the drafting head. In some positions, however, the spring may exert more pull than that required to balance the head and tend to pull the head upwardly. The piano wire 28 flexes in response to such pull and relieves the tension of the spring. This prevents instability of the head when the spring 24 is under such excessive tension although the rod 28 normally provides a fixed path for the trolley 27.

This rod 28 is clamped to the bracket 2 by means of a screw 29 which fixes its position once its curved portion has been properly oriented.

When the parallelogram links 3 and 4 are inclined to the left or to the right of the vertical X-Y, the trolley 27 is automatically displaced to the left or to the right along the curve of the rod 28, in such a manner that the axis of the spring 24 is always directed along the normal to this curve. Thus, e. g. in the dotted position of the first parallelogram in the figure, the trolley 27 has moved to the position 27'.

The tension of the spring, represented by the vector OR, may be resolved into two components OM and ON.

The component OM applied to the block 9 is without effect, being directed towards the points 5 and 6, whereas the component ON applied to the block 9 counterbalances the effect of the weight of the parallelogram links 3 and 4, the block 9, and the parts carried thereby.

The action would be the same for a position of the parallelogram links 3 and 4 to the left of the vertical, the trolley 27 then passing to the left-hand part of the rod 28.

The parallelogram links 10 and 11 and head 13 likewise tend to fall of their own weight. The wire 20 exerts a force represented by the vector O'R' upon the point 15 and this may be resolved into its two components O'M' and O'N'. The latter opposes the effect of gravity upon the head 13 and the parts carried thereby.

The explanation just given of the modus operandi of the spring is intended solely to convey an understanding of its counteractive effect against gravity, but a thorough stress analysis would show that in the various positions which the instrument may occupy on the surface of the board, a balance is obtained which, while not perfect, is amply sufficient for practical purposes.

The spring may be fitted with a simple and known device with which it is possible, for a given inclination of the board, to obtain a suitable tension relative to that inclination.

The arrangement which has been described may of course, without transcending the scope of the invention, be adapted to the various known forms of jointed drafting instruments.

It will be noted in particular that the device described has a single spring for balancing the two arms. However, it would not be beyond the scope of the present invention to modify the same by limiting the action of the spring 24 to the balancing of the upper arm, attaching it to a fixed point on the block 9, and accomplishing the balancing of the lower arm by means of an independent spring attached to another fixed point on the block 9.

The system described is simple, and practical, and is suited to commercial use.

What is claimed is:

1. A drawing board having an instrument mounted on a member to swing with a parallel motion over the surface of the board, and a spring attached at one end to said member and adapted to exert a pull for balancing the weight of said member, an anchor for the other end of said spring and a curved flexible wire track

supporting said anchor for movement along a normally fixed path in response to the swinging of said member, said path being selected to cause the spring to oppose the effect of gravity in all positions of said member, said wire being deformable in response to an excessive pull of said spring caused by said member when in certain positions.

2. In a drawing board, a pair of parallelogram links pivoted to swing thereover and carrying a block, a second pair of parallelogram links pivoted to said block and carrying a drafting head, a pulley on said block, a flexible tension member attached to said head and extending around said pulley, said tension member being adapted to exert a pull for balancing the weight of said head a trolley attached to the free end of said tension member, a flexible wire supporting said trolley for movement along a normally fixed path in response to the swinging of said block, said path being selected to cause said tension member to oppose the effect of gravity in all positions of said head and being deformable in response to an excessive pull of said tension member caused by said head when in certain positions.
